BURTON BOGARDUS BEAN, OF NEW HAVEN, CONNECTICUT.

VALVE-GRINDING TOOL.

1,212,002.

Specification of Letters Patent. Patented Jan. 9, 1917.

Application filed May 4, 1916. Serial No. 95,351.

To all whom it may concern:

Be it known that I, BURTON B. BEAN, a citizen of the United States, and a resident of New Haven, in the county of New Haven and State of Connecticut, have invented a new and Improved Valve-Grinding Tool, of which the following is a full, clear, and exact description.

The object of the invention is to provide 10 a new and improved valve grinding tool more especially designed for grinding valves of internal combustion engines such, for instance, as are used in automobiles, motor boats and the like, and arranged to permit 15 the user to readily grip and turn the valve in its seat and to allow of occasionally lifting the valve to facilitate accurate grinding of the valve in the seat.

In order to accomplish the desired result, 20 use is made of a split body provided with depending gripping means adapted to engage the valve to be ground, the gripping means being located on opposite sides of the split, and a clamping screw on the said body 25 and extending across the split near the outer end thereof to allow of drawing the split members of the body toward each other to firmly engage the gripping means with the valve to be ground. Use is also made of a 30 peculiarly shaped handle attached to the body of the grinding tool to allow of conveniently rotating the tool and the valve with which it is engaged at the time.

A practical embodiment of the invention 35 is represented in the accompanying drawings forming a part of this specification, in which similar characters of reference indicate corresponding parts in all the views.

Figure 1 is a sectional elevation of the 40 valve grinding tool as applied to the valve of an internal combustion engine; Fig. 2 is a side elevation of the same with the body of the grinding tool and the valve seat shown in section; Fig. 3 is a sectional plan view of 45 the same on the line 3—3 of Fig. 2; and Fig. 4 is a cross section of the same on the line 4—4 of Fig. 2.

The body 10 of the valve grinding tool is 50 made in disk shape and has its bottom 11 concave to snugly fit onto the top of the valve 12 to be ground in its valve seat 13. The body 10 is provided with a slot 14 extending from the edge of the disk diametrically across the same to within a distance 55 of the other side, the slot terminating in an

opening 15 extending through the disk in a vertical direction so that two clamping jaws 16 and 17 are provided on the disk body 10. The outer or free ends of the jaws 16 and 17 are connected with each other by a clamping 60 screw 18 which extends at a right angle across the slot 14 to permit of moving the jaws 16 and 17 toward or from each other.

The under side of the body 10 is provided with gripping means for engaging the valve 65 12 and the said gripping means are preferably in the form of a pair of keys 19, 20 depending from the under side 11 of the body 10 and locked on the jaws 16 and 17, that is, at opposite sides of the slot 14. The 70 gripping keys 19 and 20 extend in a diametrical line at a right angle to the diametrical slot 14 as will be readily understood by reference to Fig. 3, and the lower projecting ends of the keys 19 and 20 are adapted to 75 engage key recesses 21 and 22 formed in the upper face of the valve 12, as will be readily understood by reference to Fig. 1. When the gripping keys 19 and 20 are engaged with the recesses 21 and 22 then the jaws 16 80 and 17 are in their normal open position, and after the gripping keys 19 and 20 have been engaged with the said recesses 21 and 22 then the clamping screw 18 is screwed up to move the jaws 16 and 17 toward each 85 other whereby the gripping jaws 19 and 20 are moved in a like direction to cause the projecting ends of the gripping keys 19 and 20 to bind in the recesses 21 and 22 thus 90 securely locking the body 10 to the valve 12 to permit of rotating the latter in its seat 13 and to lift the valve off the said seat from time to time during the grinding operation.

The body 10 is provided with a pivot pin 95 25 extending diametrically at a right angle across the slot 14 at the middle of the disk body 10, that is, in alinement with the gripping keys 19 and 20, and on this pivot pin 25 is fulcrumed the shank 26 of a handle 27 provided at its lower end with a flange 28 100 adapted to form a convenient rest for the two hands of the operator having hold of the handle 27 between the hands to allow of rotating the handle and with it the tool and the valve. By the arrangement described, 105 the handle 27 is free to swing on its pivot 25 to hold the handle at any desired angle relative to the axis of the body 10 and the valve 12 to exert more or less pressure at one side or the other as the case may be. It will 110

also be noticed that by the operator having hold of the handle 27 between the two hands the tool and the valve can be readily rotated or the valve temporarily lifted off its seat 5 and then returned to facilitate accurate grinding of the valve in the seat 13. After the valve is properly ground in its seat the operator unscrews the clamping screw 18 to release the keys 19 and 20 relative to the 10 key recesses 21 and 22 thus permitting convenient lifting of the body 10 out of engagement with the valve 12.

The valve grinding tool shown and described is very simple and durable in construction and composed of comparatively few parts not liable to get easily out of order.

Having thus described my invention, I claim as new and desire to secure by Letters Patent:—

1. A valve grinding tool, comprising a split body provided with depending gripping means adapted to engage the valve, the gripping means being located on opposite 25 sides of the split, and a clamping screw on the said body and extending across the split near the outer end thereof and parallel to a vertical plane passing through the axes of the said gripping means to allow of drawing 30 the split members of the body toward each other to firmly engage the gripping means with the valve to be ground.

2. A valve grinding tool, comprising a disk provided with a slot extending diametrically from the peripheral edge of the disk to within a distance of the edge at the opposite side, the said slot providing the disk 35 with a pair of jaws, gripping keys depending from the jaws and adapted to engage key recesses in the valve to be ground, and a clamping screw engaging the jaws near 40

the free ends thereof and extending across the slot.

3. A valve grinding tool, comprising a disk provided with a slot extending diametrically from the peripheral edge of the disk to within a distance of the edge at the opposite side, the said slot providing the disk 45 with a pair of jaws, gripping keys depending from the jaws and adapted to engage key recesses in the valve to be ground, the said gripping keys extending in a diametrical line at a right angle to the said slot, a clamping screw engaging the outer free ends 50 of the jaws and extending across the slot, a pivot held in the disk and extending at a right angle across the slot in alignment with the said gripping keys, and a handle having a shank extending into the slot and pivoted on the said pivot.

4. A valve grinding tool, comprising a disk provided with a slot extending diametrically from the peripheral edge of the disk to within a distance of the edge at the opposite side, the said slot providing the disk 55 with a pair of jaws, gripping keys depending from the jaws and adapted to engage key recesses in the valve to be ground, the said gripping keys extending in a diametrical line at a right angle to the said slot, a clamping screw engaging the outer free ends 60 of the jaws and extending across the slot, a pivot held in the disk and extending at a right angle across the slot in alignment with the said gripping keys, and a handle having a shank extending into the slot and pivoted on the said pivot, the said handle having an annular bottom flange for the hands of the operator to rest on while turning the handle.
